ILLUMINATED SIGN

Filed Oct. 19, 1925

Fig. 1.

Patented Sept. 27, 1927.

1,643,506

UNITED STATES PATENT OFFICE.

ELMO P. MACNICOL, OF MEMPHIS, TENNESSEE.

ILLUMINATED SIGN.

Application filed October 19, 1925. Serial No. 63,418.

The invention relates to illuminated signs, and has for its object to provide a device of this character particularly adapted for use in vehicles, comprising an elongated frame for the reception of signs and the lower rail of the sign with a longitudinally extending light box, in which electric lamps may be placed and which box reflects light rays upwardly onto the sign, thereby allowing the same to be easily read at night.

A further object is to provide an illuminated sign comprising an elongated rectangular shaped frame formed from channel material, the outer flange of which is provided with longitudinally extending crimps thereby forming conduits for electric conductors and with outwardly struck light boxes carried by the lower rail in which electric bulbs may be placed, and electric conductors therefrom which extend longitudinally through the conduits formed by the crimps. The crimp in the bottom rail forms a conduit which is only interrupted by the outwardly struck light boxes.

With the above and other objects in view the invention resides in the combination and arrangement of parts as hereinafter set forth, shown in the drawing, described and claimed, it being understood that changes in the precise embodiment of the invention may be made within the scope of what is claimed, without departing from the spirit of the invention.

In the drawing:—

Figure 1 is a perspective view of the display sign.

Figure 2 is a vertical transverse sectional view taken on line 2—2 of Figure 1.

Figure 3 is a perspective view of another form of the device, showing outwardly struck light boxes carried by the lower rail thereof.

Figure 4 is a vertical transverse sectional view taken on line 4—4 of Figure 3.

Figure 5 is a vertical transverse sectional view taken on line 5—5 of Figure 3.

Referring to the drawings and particularly to Figures 1 and 2 the numeral 1 designates an elongated oblong shaped frame, which is angular in transverse cross section, and disposed within the frame behind the front flange 2 thereof, are signs 3 on which any subject matter may be printed. The signs 3 are separated and held

against outward bulging by flexible strips 55 4, which engage the inner sides of the flanges 2 as clearly shown in Figure 2. Disposed within the rear side of the frame 1 is a backer 5 which is held in place, preferably by lugs 6 bent against the rear side 60 thereof, therefore it will be seen that the signs 3 are rigidly held and are maintained flat at all times whereby when light is projected onto the same, shadows will not be formed. 65

It is obvious that at night means must be provided for illuminating the sign sections 3, and to accomplish this result and at the same time prevent downward deflection of light rays, the lower flange 2 is provided with a longitudinally extending reflecting light box 7, the upper side of which is open, and disposed within the light box 7 are electric lamps 8, the light rays from which are reflected upwardly onto the signs 75 3, and downward projection of light rays is prevented, therefore it will be seen that objectionable light rays downwardly will be cut off from the eyes of the occupant of the vehicle, and at the same time the display 80 cards will be thoroughly illuminated without any shadows thereon.

Referring to Figures 3 to 5 inclusive wherein another form of device is shown, the construction is substantially the same 85 as shown in Figure 1, except the flange 2^a has its lower horizontal portion provided with struck out pockets 9, which form light boxes for the electric lamps 8^a, and the flange 2^a is longitudinally crimped, thereby 90 forming an electrical conductor conduit 10 extending the full length of the lower portion of the frame, and which is only interrupted at the light boxes 9, and through which conduit 10 a conductor wire 11 ex- 95 tends to the electric lamps 8^a, consequently the wire 11 is concealed from view at all times and will not detract from the appearance of the device. In this form of the device the light rays are projected upwardly 100 onto the signs 3, and at the same time downward projection of rays from the electric lamps 8^a is obviated. As the other construction of the sign is the same as that shown in Figure 1 the same numerals apply thereto. 105 By striking out the pockets 9 it is obvious the frame 1 may be formed from a single piece of metal and stamped in a single oper-

ation, thereby reducing the cost of manufacture to a minimum and allowing the device to be cheaply manufactured and sold.

The invention having been set forth what is claimed as new and useful is:—

1. The combination with a display sign frame having a lower rail, of light boxes integrally formed with said rail, said rail being crimped longitudinally thereby forming conductor conduits connecting the chambers of the light boxes.
2. A display sign comprising a rectangularly shaped frame having a lower rail, said frame being angularly shaped in cross section, thereby forming a channel in which sign sections are received, the outer flanges of said frame being longitudinally crimped

thereby forming longitudinally extending conductor wire conduits, the outer flange of the lower rail of the frame being provided with outwardly light boxes having their upper sides open.

3. The combination with the lower rail of a display sign frame, said rail having its inner side provided with a longitudinally disposed conductor channel, of outwardly struck light boxes carried by said rail and having chambers in connection with the conductor wire channel.

In witness whereof, I have hereunto set my hand at Memphis, Tennessee, this 30 day of September, 1925.

ELMO P. MACNICOL.
